UNITED STATES PATENT OFFICE

HAROLD A. GREENWALD, OF DETROIT, MICHIGAN, ASSIGNEE, BY MESNE ASSIGNMENTS, TO KELVINATOR CORPORATION, OF DETROIT, MICHIGAN, A CORPORATION OF MICHIGAN

REFRIGERATOR CABINET CONSTRUCTION

Application filed March 31, 1930. Serial No. 440,557.

This invention relates generally to refrigerator cabinets and refers more particularly to those designed for use within walls or cupboards.

Heretofore it has been customary when installing refrigerating apparatus on or in refrigerating cabinets to mount the refrigerant low side such as the cooling coils or chamber within the food compartment or in a cooling chamber of the cabinet and to mount the refrigerant high side such as the compressor and condenser either on top or at the bottom of the cabinet. Ordinarily it was difficult to install the machine upon or to remove it from the top of the cabinet. In fact, it has been necessary sometimes to use derricks and/or cranes to effect the desired installation or removal of the high side parts. The space occupied was great since it was necessary to allow not only the actual space required by the cabinet and machine, but also sufficient space for installing or removing the machine and a large space for air circulation, especially where convection currents in the air were depended upon. Moreover, the space above the cabinet about the apparatus could not be used satisfactorily as cabinet or cupboard space, hence was wasted. In addition such installations usually included box-like covers or cages for the machine, and such enclosures were unsightly. When placed at the bottom of the cabinet the machine occupied space which might otherwise have been useful for cupboard space or for receiving foods, and from an efficiency standpoint was objectionable. Due to the location and arrangement of parts the entire machine could not be installed in or removed from the cabinet without making or breaking pipe connections, with the consequent chances of gas and oil escaping or dirt and moisture entering the system. This required skilled workmen. In fact such workmen had to leave the service station or factory to travel to and from installations and thereby consumed such time in just traveling as truck drivers back and forth between jobs. Consequently such workmen were unable to devote their entire time to

skilled work and were expensive to maintain.

With the present invention, however, the cabinet receives both the high and low sides of the apparatus and also receives air from the atmosphere for cooling the high side and effecting the desired condensation of the refrigerant therein, hence my improved construction obviates the necessity for space on top, about or at the bottom of the cabinet for refrigerating apparatus. Moreover, the cabinet may fit snugly within an opening of substantially corresponding size in a wall or cupboard and the maximum food compartment and cupboard space is obtained.

In the accompanying drawings:

Figure 1 is a front elevation of a cabinet embodying my invention;

Figure 1A is a view similar to Figure 1 but showing a slightly modified construction;

Figure 2 is a side elevation thereof;

Figure 3 is a vertical transverse sectional view through the cabinet;

Figure 4 is a vertical sectional view taken at right angles to Figure 3;

Figure 4A is a detail sectional view taken on the line A—A of Figure 4;

Figure 5 is a vertical sectional view through the cabinet and showing refrigerating apparatus therein;

Figure 6 is a top plan view of the construction illustrated in Figure 5;

Figure 7 is a front elevation of the cabinet with the door open and showing refrigerating apparatus therein;

Figure 8 is an enlarged fragmentary vertical sectional view through the upper portion of the front wall of the cabinet;

Figure 9 is a fragmentary front elevation of a slightly modified construction of louvers for the front wall of the cabinet;

Figure 10 is a top plan view of the construction illustrated in Figure 9.

Referring now to the drawings, 1 is a cabinet adapted to fit snugly within an opening of substantially corresponding size in a wall or cupboard and having an open top chamber 2 for refrigerating apparatus and a compartment 3 for food. As shown, the cham-

100

ber 2 projects forwardly from the rear wall 4 of the cabinet adjacent the top wall 5 and has an opening 6 in its front wall 7, while the 5 food compartment 3 is in front and below the chamber 2 and has an opening 8 in the front wall 9. The base 10, compressor 11, motor 12, fan 13, condenser 14 and expansion valve 15 of a portable refrigerating apparatus such as that set forth in my companion application Serial No. 440,558 are received within the 10 chamber 2, while the cooling element 16 of the apparatus is received within the food compartment 3 and has a tray compartment opening 17 in its front wall adjacent the 15 opening 8 in the front wall 9. The trim panel 18 between the cooling element 16 and the base 10 of the portable apparatus normally closes the opening 6 in the chamber 2, while a door 19 closes the opening 8 in the 20 front wall 9. Preferably the door is received in the opening 8 in the front wall so that the inner face 20 thereof closes the tray compartment opening 17 in the cooling element, and the outer face 21 thereof is 25 substantially flush with the outer face 22 of the wall 9. Thus the construction of the chamber 2 and the location of the opening 6 in the front wall thereof relative to the opening 8 in the front wall of the cabinet is 30 such that the portable apparatus may be easily and conveniently moved through the opening 6 in the front wall of the cabinet to or from the chamber 2. This is one of the 35 features that enables the cabinet to fit snugly within an opening in a wall or cupboard.

In the present instance the door 19 and the front wall 9 at the sides and bottom of the opening 6 are provided between their inner and outer faces with bodies 23 and 24 respectively of insulating material such as cork. Above the opening 6 the front wall 9 has a bar 25 of wood that is spaced from the top wall 5 and is terminally connected to the side walls 26 and 27 respectively. Preferably this bar 25 is provided throughout its length with a substantially L-shaped rabbet 28 that opens upwardly and outwardly and receives an electric switch or "cold control" 29 for the motor 12 in the chamber 2. This 40 switch 29 is mounted in the front wall 9 opposite the center of the bar 25 and is connected by suitable conductors (not shown) to the motor. A partition 30 having a body 31 of insulating material extends horizontally 45 between the bar 25 and the front wall 7 of the chamber in spaced relation to the top 5 and constitutes a portion of the ceiling of the food compartment 3. The bottom 32 of the chamber constitutes the other 50 portion of the food compartment ceiling.

60 Preferably the bottom 32 of the chamber 2, the upright wall 33 carried by the refrigerating apparatus base 10, the bottom wall 34 of the cabinet, a portion 35 of the rear wall between the chamber bottom 32 and the

bottom wall 34 of the cabinet, and portions 65 36 and 37 respectively of the side walls 26 and 27 located in front of and below the chamber 2 contain insulating material such as cork. Thus the food compartment 3 is 70 insulated from the chamber 2 and from the outside atmosphere. Moreover the inner faces 41, 42, 43, 44, 45, 46 and 47 respectively of the door 19, partition 30, trim panel 18, chamber bottom 32, side wall portions 36 and 37, and rear wall portion 35 are porcelain and provide a neat sanitary and attractive appearance.

In order that the refrigerating parts such as the condenser 14, compressor 11, etc., with- 80 in the open top chamber 2 may be effectively cooled by fresh air from the atmosphere, the front wall 9 is provided above the opening 8 upon opposite sides of the switch 29 with laterally spaced louvers 48 and the space be- 85 tween the horizontal partition 30 and the top 5 of the cabinet is divided by a vertical partition 49 into two passageways 50 and 51 respectively whereby air from the atmos- 90 phere may be drawn by the fan 13 through the louvers 48 upon one side of the switch 29 and through the passageway 50 to the open top chamber 2 and will be forced by the fan 95 through the chamber 2 and thence outwardly through the passageway 51 and louvers 48 upon the other side of the switch. Hence air for cooling the refrigerating apparatus and effecting the desired condensation of refrigerant in the condenser 14 is drawn 100 through and discharged from the front wall 9 of the cabinet. This is another of the features that enables the cabinet to fit snugly within an opening in a wall or cupboard. In this connection air from the atmosphere 105 may be directed to and from the chamber 2 by other means such as conduits (not shown) extending through the flooring (not shown) upon which the cabinet rests or is supported. Preferably the partition 49 extends between the front and rear walls 9 and 4 respectively 110 of the cabinet and is provided at its rear end with a depending portion 52 that serves as a vertical partition in the upper portion of the chamber 2. A second vertical partition 53 overlaps this depending portion 52 and cooperates therewith to cause air from the 115 passageway 50 to pass downwardly and through the condenser 14 and about the motor 12 and compressor 11 before passing outwardly through the passageway 51.

In Figures 9 and 10 I have illustrated a modified construction in which the louvers 60 extend horizontally and open downwardly and constitute outward embossed portions of a sheet metal plate 61 secured by screws 62 to the front of the cabinet.

While it is believed that from the foregoing description the nature and advantages of the invention will be readily apparent, I desire to have it understood that I do not 130

limit myself to what is herein shown and described and that such changes may be resorted to when desired as fall within the scope of what is claimed.

5. What I claim as my invention is:

1. A refrigerator cabinet having as a rigid part thereof a food compartment opening and a chamber for refrigerating apparatus, the chamber having an opening in line with said opening, and means independent of the opening for conducting air from a suitable source to the chamber to cool refrigerating apparatus therein.

15. A refrigerator cabinet having an opening in an upright wall thereof, a food compartment in rear of said opening, and a chamber for refrigerating apparatus in rear of said compartment and having an opening in alignment with the opening aforesaid 20 establishing communication between said chamber and food compartment.

25. A refrigerator cabinet having a food compartment provided with an opening, and having a chamber for refrigerating apparatus opening into said compartment in substantially horizontal alignment with the opening aforesaid so that refrigerating apparatus may be moved through the said compartment opening to and from the chamber.

30. 4. A refrigerator cabinet having a food compartment, a chamber for refrigerating apparatus in a horizontal plane with a portion of the compartment, and means between the compartment and a wall of the cabinet 35 for conducting air from the atmosphere to the chamber to cool apparatus therein.

5. A refrigerator cabinet having a compartment for food, a chamber for refrigerating apparatus, openings in an upright wall 40 thereof, one of said openings constituting a common passageway for food and refrigerating apparatus to and from the compartment and chamber respectively, and means associated with other of said openings for conducting air from the atmosphere to and from the chamber to cool refrigerating apparatus therein.

6. A refrigerator cabinet having a chamber for refrigerating apparatus projecting 50 forwardly from the rear wall thereof, a passageway for air extending from the front wall thereof to the chamber, and a food compartment at one side of the chamber and having a wall thereof constituting one side of the 55 passageway aforesaid.

7. A refrigerator cabinet having a plurality of openings in an upright wall thereof and provided in rear of said wall with a food compartment and a chamber for refrigerating apparatus, one of said openings constituting an opening for the food compartment and a passageway for refrigerating apparatus to and from the chamber, another of said openings constituting an air 65 inlet, a connection between said inlet and

chamber, another of said openings constituting an air outlet, and a connection between said outlet and the chamber.

8. A refrigerator cabinet of substantially rectangular configuration having as a rigid 70 part thereof a compartment for food and a chamber for refrigerating apparatus, one being in rear of the other and having an opening communicating therewith whereby it is accessible through the other.

9. A refrigerator cabinet having an opening in its front wall and having another opening, said cabinet having a partition dividing it into two compartments, one of 75 said compartments being accessible through one of said openings, and the other compartment being accessible from the first compartment and in communication with the second mentioned opening.

10. A refrigerator cabinet having openings 80 in an upright wall thereof, a food compartment in rear of and accessible through one of said openings, a chamber for refrigerating apparatus in rear of said compartment and having an opening in its front wall in substantial alignment with the opening aforesaid whereby refrigerating apparatus may be moved through the compartment opening and the opening in the chamber to and from the latter, and means associated with another 85 of the first mentioned openings in said upright wall for conducting air from the atmosphere around a portion of the compartment to and from the chamber.

11. A refrigerator cabinet having openings 90 in an upright wall thereof, a food compartment in rear of and accessible through one of said openings, a chamber for refrigerating apparatus in rear of said compartment and having an opening in its front wall in substantial alignment with the opening aforesaid whereby refrigerating apparatus may be moved through the compartment opening and the opening in the chamber to and from the latter, and passages associated 95 with another of the first mentioned openings in said upright wall for conducting air from the atmosphere around a portion of the compartment to and from the chamber.

12. A refrigerator cabinet having a food compartment accessible through an opening 100 in its front wall and having a compartment for refrigerating apparatus in rear of the food compartment and accessible from the food compartment.

13. A refrigerator cabinet having an upright wall provided with an opening and a group of openings, a food compartment in rear of and accessible through the first mentioned opening, and a chamber for refrigerating apparatus in rear of and opening into the food compartment and in communication with the group of openings aforesaid.

14. A cabinet having front and rear walls, 105 and a substantially vertical partition inter-

mediate said walls and provided with substantially horizontal stepped portions respectively that extend forwardly and rearwardly from the partition to the front and rear walls

5 aforesaid.

15. A cabinet having a food compartment accessible through the front wall of the cabinet and having a chamber for refrigerating apparatus in rear of said food compartment

10 and accessible only from said food compartment.

16. A substantially rectangular refrigerator cabinet having an opening in one upright wall thereof and provided intermediate its top and bottom walls with a stepped partition that divides the cabinet vertically into two compartments and that has an opening in the upright portion thereof in substantial alignment with the opening in the upright wall of the cabinet, whereby refrigerating apparatus and the like may be moved through said aligned openings.

In testimony whereof I affix my signature.

HAROLD A. GREENWALD.
